DESIGN FOR A RING WATCH

Bennie Hurd, Chicago, Ill.

Application November 3, 1945, Serial No. 123,440

Term of patent 14 years

(Cl. D42—8)

To all whom it may concern:

Be it known that I, Bennie Hurd, a citizen of the United States, residing at Chicago, in the county of Cook, State of Illinois, have invented a new, original, and ornamental Design for a Ring Watch, of which the following is a specification, reference being had to the accompanying drawing, forming a part thereof.

In the drawing, Fig. 1 is a top plan view of a ring watch showing my new design; Fig. 2 is a front elevation of the ring watch; and Fig. 3 is a side elevation thereof.

I claim:

The ornamental design for a ring watch, as shown.

BENNIE HURD.
